UNITED STATES PATENT OFFICE.

JOHANN ERNST, OF PADERBORN, GERMANY.

EXHAUST-SILENCER.

1,388,107.

Specification of Letters Patent. Patented Aug. 16, 1921.

Application filed August 11, 1919. Serial No. 316,904.

To all whom it may concern:

Be it known that I, JOHANN ERNST, a citizen of the German Republic, and residing at Paderborn, Germany, have invented certain new and useful Improvements in Exhaust-Silencers, of which the following is a specification.

This invention relates to an improved exhaust-silencer of the type comprising an incased helix for offering a vigorous resistance to the escaping exhaust-gases and thereby silencing the same.

The essence of the invention consists in making said helix of a bulb formation on the side facing its outlet-end, further of double-cone shape, thirdly of a pitch increasing from its middle toward both ends, and fourthly with a central bore which is cylindrical in its middle and conically increased toward both ends.

Thereby, the exhaust-gases flowing through said helix are set in whirling motion and find an effective resistance on the bulbed walls of the helix, which is the greatest at the middle of the latter, where the pitch of the helix is very low and the central bore rather small, while the admission as well as the escape of the exhaust-gases is facilitated by the pitch of the helix as well as its central bore being gradually increased toward its inlet and outlet ends. Owing to the double-cone shape of the helix and the different areas between the single threads of the helix, the exhaust-gases receive, moreover, different kinds of movement during their way through the latter. By the particular design of helix, dead angles are avoided and a settling-down of the products of combustion does not take place.

The dimensions of the improved exhaust-

silencer are so determined that the exhaust is still audible with a low speed of the motor, for controlling the proper working of the latter, while with a high speed a perfect silencing is obtained.

In the accompanying drawing:

Figure 1 is a central section through the improved exhaust-silencer, while

Fig. 2 is an end-view of one half of the same.

The arrow 1 indicates the admission-orifice of the exhaust-silencer; 2 designates the open-ended casing of the same of double-cone shape, which consists of two parts screwed together; 3, 4, 5, 6, 7, 8, 9, 10 are the single threads of the helix of double-cone shape with increasing pitch toward both ends and which are bulbed on the side facing the outlet-orifice of the casing; 11, 12, 13, 14 indicate the central bore through the helix, which is cylindrical in its middle and conically increased toward both ends.

What I claim, is:—

An exhaust-silencer, comprising, in combination, an open-ended casing of double-cone shape and a correspondingly shaped helix therein of a bulb formation on the side facing its outlet-end and of a pitch increasing from its middle toward both ends, said helix having a central bore therein which is cylindrical in its middle and conically increased toward both ends, substantially as and for the purpose set forth.

In testimony whereof I have hereunto set my hand in the presence of two subscribing witnesses.

JOHANN ERNST.
